(57) **CLAIM**

The ornamental design for a manifold for supplying coolant to components of substrate processing systems as shown and described.

DESCRIPTION

FIG. 1 is a perspective view of a manifold for supplying coolant to components of substrate processing systems; FIG. 2 is a front view of the manifold shown in FIG. 1; FIG. 3 is a back view of the manifold shown in FIG. 1; FIG. 4 is a top view of the manifold shown in FIG. 1; FIG. 5 is a bottom view of the manifold shown in FIG. 1; FIG. 6 is a left side view of the manifold shown in FIG. 1; and, FIG. 7 is a right side view of the manifold shown in FIG. 1. The dash-dash broken lines in the drawings illustrate portions of the article that form no part of the claimed design.
